UNITED STATES PATENT OFFICE

117,719

DESIGN FOR AN IMPELLER

Alexander J. McDonald, Denver, Colo.

Application October 21, 1938, Serial No. 80,588

Term of patent 14 years

To all whom it may concern:

Be it known that I, Alexander J. McDonald, a citizen of the United States, residing at the city and county of Denver, and State of Colorado, have invented a new, original, and ornamental Design for Impellers, of which the following is a specification, reference being had to the accompanying drawing, forming part thereof.

In the drawing

Figure 1 is a perspective view of an impeller showing my new design;

Figure 2 is a top plan view thereof; and
Figure 3 is a side elevation, partly in section.

I claim:

The ornamental design for an impeller, as shown.

ALEXANDER J. McDONALD.
